UNITED STATES PATENT OFFICE.

EDWIN S. HAFF, OF BROOKLYN, NEW YORK.

DESIGN FOR A CAKE OF CHEWING-GUM, &c.

SPECIFICATION forming part of Design No. 28,207, dated January 25, 1898.

Application filed July 12, 1897. Serial No. 644,341. Term of patent 14 years.

To all whom it may concern:

Be it known that I, EDWIN S. HAFF, a citizen of the United States, and a resident of Brooklyn, in the county of Kings and State of New York, have invented and produced a new and original Design for Cakes of Chewing-Gum and Confectionery, of which the following, taken in connection with the accompanying drawings, is a specification.

- 10 In the drawings, Figures 1 and 2 are side elevations of opposite sides of the design, respectively; and Fig. 3, a vertical sectional elevation thereof, taken in the plane xx of Fig. 1.
- 15 The leading feature of my design consists in a general crown-shaped body which is composed of a suitable base and two converging elliptic spheroidal-shaped portions extending upward and outward therefrom, with a similarly-shaped ornament arranged between them and surmounting the central portion of the design.
- 20 a indicates the base of the design, which consists of a band that is scalloped or indented around its upper edge, and $b b$ two elliptic spheroidal-shaped lobe-like portions which

extend upward and outward from the base in converging directions. Extending across between these portions $b b$ is a thin web c , which supports over the center of the base a 30 an elliptic spheroidal-shaped ornament d , and has formed upon each of its sides an ornamental tri-armed projection e , the arms of which extend outward toward and connect with the lobes $b b$ and the ornament d , forming therewith an ornamentation that is both graceful and extremely attractive in appearances.

Having now described my invention, I claim—

40 A design for cakes of chewing-gum and confectionery, consisting in a general crown-shaped body, which is composed of the base a , the elliptic spheroidal-shaped lobes $b b$, the web c , and the elliptic spheroidal-shaped 45 mounting ornament d , as set forth.

In witness whereof I have hereunto set my hand this 8th day of July, 1897.

EDWIN S. HAFF.
